UNITED STATES PATENT OFFICE.

HEINRICH MICHELSTÄDTER AND HANS CHRISTIAN, OF VIENNA, AUSTRIA-HUNGARY.

SHOE-STRAINING DEVICE.

SPECIFICATION forming part of Letters Patent No. 700,065, dated May 13, 1902.

Application filed December 14, 1901. Serial No. 85,895. (No model.)

To all whom it may concern:

Be it known that we, HEINRICH MICHELSTÄDTER, manufacturer, residing at VII, Neubaugasse No. 57, and HANS CHRISTIAN, gentleman, residing at Halbgasse No. 6, Vienna, Austria-Hungary, citizens of Austria-Hungary, have invented certain new and useful Improvements in Shoe-Straining Devices; and we hereby declare the following to be a full, clear, and exact description of the invention, such as will enable others skilled in the art to which it appertains to make and use the same.

This invention relates to shoe-straining devices, and among the objects in view is to provide a device of this character adapted for ready adjustment both longitudinally and laterally, whereby to accommodate it to shoes of different sizes.

20 A further object of the invention is to provide a device of the character described, which will be of comparatively simple construction and which is adapted to be folded into compact form when not in use.

25 The invention consists in the novel construction, arrangement, and combination of parts, as hereinafter fully described, illustrated in the drawings, and pointed out in the appended claims.

30 In the drawings, Figure 1 is a central longitudinal sectional view of the device in position for use. Fig. 2 is an under side view, partly in section. Fig. 3 is a sectional view, partly in elevation, showing the device folded.

35 Fig. 4 is a detail view of the slide *o*, showing the same in side view. Fig. 4^a shows an end view of the slide *o*. Fig. 4^b shows a horizontal section of said slide. Fig. 5 is a detail view of the part *n*, showing the same in side view. Fig. 5^a is an end view of the part *n*. Fig. 5^b is a plan view of said part.

Our improved device comprises a front or toe portion and a rear or heel portion, preferably having a jointed connection, whereby to adapt said portions to be folded, as seen in Fig. 3. The toe portion may be of one rigid piece; but we preferably construct it of two pieces *c c*, having a yielding connection, whereby to adapt said portions to have a lateral movement relatively to each other, whereby the toe portion of the device may

be readily inserted within shoes of varying widths. The yielding connection between the portions *c c* is formed by springs *b b*, the ends of which engage with pins *b'*, secured to the portions *c c*. Pins *e* are provided, engaged by the coiled portions of the springs to prevent complete disengagement of the parts *c c*.

Secured to the under side of each of the portions *c* is a U-shaped guide *d*, within which the springs *b* are guided, and said guides *d* are bent up at the rear end to form eyes *f* to receive a bolt *g*, upon which latter is pivotally mounted one end of a rod *a*, and mounted upon the bolt *g* upon each side of the rod *a* is a coiled spring *h*. These springs *h* serve to maintain the rod *a* centrally upon the bolt and in proper position relatively to the portions *c*.

It will be seen that when the toe-piece is inserted within a shoe the portions *c* thereof will be compressed to adapt said toe-piece to enter the shoe, and after the device has been fully inserted the springs *b* will serve to force the portions *c* laterally, to thereby maintain the upper of the shoe in a taut or strained condition.

The heel portion *i* of the device is shaped somewhat to correspond with the rear portion or counter of a shoe, and this heel portion preferably has a jointed connection with the toe portion through the medium of the rod *a*, said connection being such as to permit the toe and heel portions to be adjusted toward and from each other, whereby to adapt the device to shoes of different lengths. The heel portion *i* is recessed, as at *j*, and at the upper portion is provided with an aperture *k*, through which loosely passes a screw-rod *m*. The latter works within a threaded portion or nut *s*, formed upon a slide *o*, which is substantially U-shaped when viewed in plan, as seen in Fig. 4. The parallel sides of the slide *o* are provided with the opposite vertical slots *r* and with opposite diagonal slots *p*.

n indicates a U-shaped metallic piece arranged within the recess *j* of the heel-piece and having flanges which are screwed to the said heel-piece, as seen plainly in Fig. 2. Said piece *n* is provided with aligned horizontal slots *t*.

u indicates a pin upon which the rear end of the rod *a* is pivotally mounted, said pin passing through the inclined slots *p* of the guide *o* and the slots *t* of the piece *n*. The slide *o* is guided in its vertical movements by means of a pin *q*, which extends through the vertical slots *r* and is secured at its ends to the piece *n*.

It will be seen that by turning the screw-rod *m* in one direction the slide *o* will be raised, and by reason of the fact that the pivotal pin or bolt *u* passes through the inclined slots *p* the said pin will be caused to be forced forwardly within the horizontal slots *t* of the piece *n*, thus causing the toe-piece of the device to be adjusted forwardly through the medium of the rod *a*, whereby the toe-piece of the straining device will be caused to be pushed forwardly within the shoe as far as possible. To permit of the easy withdrawal of the device from within a shoe, the screw-rod is rotated in reverse direction, whereby the slide *o* will be lowered, thus causing the pivotal pin *u* to ride rearward within the slots *t*, thus causing the toe-piece of the device to be drawn rearwardly through the medium of the rod *a*, after which the straining device may be readily removed.

It will be noted that by the described construction of the device the longitudinal adjustment of the toe and heel pieces is readily effected, and by reason of the yielding connection between the sections *c* of the toe-piece a yielding tension will be exerted upon the front portion of a shoe when the device is in operative position within the latter.

What we claim as new, and desire to secure by Letters Patent, is—

1. In a device of the character described, the combination with toe and heel pieces, said toe-piece comprising oppositely-arranged sections, of springs *b* arranged between the said sections, pins *b'*, *e*, secured to the sections of the toe-piece and being engaged by the springs, as described, whereby to yieldingly connect the sections of the toe-piece and permit them to be laterally moved relatively to each other and at the same time pre-

vent complete separation of said sections and a jointed connection between the toe and heel pieces.

2. In a device of the character described, the combination with a toe-piece comprising oppositely - arranged sections and springs yieldingly connecting the sections of the toe-piece to adapt them for lateral movement relatively to each other, of a bolt carried by and extending transversely of the toe-sections, a rod pivotally mounted at one end on said bolt, springs on the bolt upon opposite sides of the rod, and a heel-section to which the other end of the rod is movably connected, for the purpose set forth.

3. In a device of the character described, the combination with toe and heel pieces and a rod *a* pivotally connected at one end with the toe-piece, of a vertically-movable slide carried by the heel-piece and provided with inclined slots, a fixed guide-piece carried by the heel-piece and provided with horizontal slots, and a pin upon which the other end of the rod *a* is mounted and passing through the slots in the slide and guide-piece, and means for operating the slide.

4. In a device of the character described, the combination with toe and heel pieces, said toe-piece comprising oppositely-arranged sections having a yielding connection to adapt said sections for lateral movement relatively to each other, of pieces *d* carried by the sections of the toe-piece and provided with eyes, a pin or bolt seated within the eyes, a rod mounted at one end upon the said pin or bolt, and springs mounted upon the bolt at each side of the rod, the said rod having a pivotal and slidable connection with the heel-piece, as and for the purpose specified.

In testimony that we claim the foregoing as our invention we have signed our names in presence of two subscribing witnesses.

HEINRICH MICHELSTÄDTER.
HANS CHRISTIAN.
